FIG. 4.

UNITED STATES PATENT OFFICE.

THOMAS V. ALLIS, OF BRIDGEPORT, CONNECTICUT.

FURNACE FOR ROLLING-MILLS.

SPECIFICATION forming part of Letters Patent No. 699,127, dated May 6, 1902.

Application filed April 20, 1899. Serial No. 713,764. (No model.)

To all whom it may concern:

Be it known that I, THOMAS V. ALLIS, a citizen of the United States, and a resident of Bridgeport, in the county of Fairfield and 5 State of Connecticut, have invented certain new and useful Improvements in Furnaces for Rolling-Mills, of which the following is a specification.

My invention relates to an improvement in 10 furnaces to be used in connection with rolling-mills; and it consists in an improvement on the device shown and described in a former application filed by me March 7, 1896, Serial No. 582,169.

15 To enable others to understand my invention, reference is had to the accompanying drawings, in which—

Figure 1 represents a broken upper plan view of the furnace, showing a portion of the 20 detachable roof, floor, and the interior arrangement of the several parts of the furnace beneath the floor. Fig. 2 is a broken side elevation of the furnace completely roofed in looking in the direction of arrow *a* of Fig. 1. Fig. 3 is an upper broken view of the furnace 25 with the roof removed, showing the floor completely covered with the several strips or bars to be heated. Fig. 4 is an end elevation of the complete furnace looking in the direction 30 of arrow *b* of Fig. 1. Fig. 5 is a transverse section through line *c* of Fig. 1. Fig. 6 is a broken detail sectional view of a branch gas-pipe, overlying iron plate, brickwork overlying said plate, sectional view of one of the 35 special fire-bricks, and side elevation of one of the gas-burners.

Its construction and operation are as follows:

1 represents tubular bars or pipes, each of 40 which carries a series of bricks 2, which unitedly comprise the roof of the furnace. These bricks have holes through them, by means of which they are strung upon the several bars and are retained there by means 45 of the washers 3 and keys 4. The outer bricks of each of the individual sections of which the roof is composed rest upon the side linings 5 and 6 of the furnace. This feature of construction is particularly adapted to wide 50 furnaces and avoids the necessity of arching the roof, and thereby decreases the air-space between the roof and the work to be heated.

Besides, there is an additional advantage in thus supporting the roof-bricks in sections, as it facilitates the instant removal of one burned 55 section and replacing it by a new one.

7 represents the metal sides of the furnace, and 8 represents brackets to which the tie-rods 9 are attached.

10, Figs. 2 and 5, is the main gas-receiver, 60 which connects with the large longitudinal delivery-pipe 11. (See also Fig. 1.) This large delivery-pipe is part of the perforated cast-iron bottom 12, and immediately overlying this frame are the metal plates 13. The 65 branches 12^a have, Fig. 5, the gas-passages 12^b, which connect with the short burner-pipes 14, screwed into the said branches. (Shown more clearly in the enlarged view at Fig. 6.) These burner-pipes 14 also pass through holes 70 15, Fig. 1, of the metal plates 13 and also extend up into the bricks 16, which bricks form the floor of the combustion-chamber. The upper ends of these pipes 14 are provided with a right-angle bend, to which are attached 75 the burners 14^a, so as to deliver the gas-flame into the recesses 17 of the bricks 16. This arrangement of individual gas-jets plentifully distributed throughout the area below the work-supporting floor-bricks 18 will give in a 80 wide furnace a more uniform heating-surface than could otherwise be obtained.

The manner of delivering the flame into the recesses or pockets 17, against the inclined walls 17^a thereof, insures a much better distribution or diffusion of the heat in the combustion-chamber than could be obtained were the burners arranged vertically. In each alternate series or rows of the bricks 16 I prefer to alternate or reverse the position of the 85 pockets and burners (see Fig. 1) to still further facilitate the distribution of the heat.

Overlying the floor-bricks 18 are placed at intervals the bearing-bars 19, upon which will rest the bars or metal strips to be heated. 20 90 95 represents interposing blocks to prevent the shifting of the said bearing-bars when the strips or bars are introduced into the furnace. 21 represents stools for sustaining the work-supporting floor on the bricks 16.

100 My present furnace is so constructed that when ready to operate it is capable of effecting a constant delivery of properly-heated bars to the reducing-rolls. To accomplish

this, the furnace-floor is first filled with bars or strips, which are heated to the proper temperature required for rolling. The bar or strip lying in the feedway is then pushed forward by means of an ordinary push bar or rod in the hands of the operator through the throat 42, Figs. 1 and 3, into the reduction-rolls. The remaining bars are then shifted laterally toward the feedway, and as fast as one bar is thus brought into the feedway and delivered therefrom through said throat 42 it is replaced by the adjoining bar or strip moved into position by the rams 22, and when the last bar introduced into the furnace at the side opposite the feedway has traversed the floor of the furnace and said feedway or delivery-line, it, too, is ready for the rolls. To effect this, I employ (see Figs. 3 and 5) a series of pusher-bars or rams 22, passing through the openings 23 in the side of the furnace and distributed at intervals proportionate to the length of the furnace and sufficient to move the bars in a straight longitudinal line across the floor.

25 24 is a shaft mounted in the forked brackets 25, attached to the side of the furnace. The under side of the projecting ends of these pusher-bars are provided with the rack-teeth 22^a, which teeth register with pinions 26, (see also Fig. 2,) mounted upon the shaft 24.

25^a (see also Fig. 4) is a forked bracket which supports the rear end of the shaft 24, and mounted on this shaft is the worm-gear 27, which meshes with the worm 28 on the short shaft 29, carrying the hand-wheel 30. Turning this hand-wheel will therefore rotate the shaft 24 and cause the several pusher-bars or rams to advance or recede, as required.

In Fig. 3 the furnace is shown to contain 40 eight bars or strips to be heated and rolled 31, 32, 33, 34, 35, 36, 37, and 38, which completely cover the floor from side to side, except the narrow openings 39 and 40, provided for the heat to rise from below. When, therefore, the bars have become sufficiently heated 45 to be acted upon by the reduction-rolls, which fact can be ascertained by simply uncovering any one of the several openings in the rear end of the furnace, which openings are 50 closed by the plugs 41, heated bar or strip 38 is pushed out through the forward opening or throat 42 to the reduction-rolls. (Not shown.) Immediately upon the delivery of this bar the pushers or rams 22 are moved forward 55 and the remaining bars are shifted, so as to place the bar 37, Fig. 5, into the place recently occupied by the bar 38. The pushers or rams are then withdrawn, and the plug 41^a farthest to the right is removed, and a fresh 60 bar is introduced to occupy the position vacated by the bar 31, and by the time this has traversed the floor of the furnace to the delivery-point it is sufficiently heated to roll. By this means there is no delay in the operation 65 of the reduction-rolls, which when once started can make a continuous run.

While I show the bars in packs, the opera-

tion, so far as the shifting mechanism is concerned, is similar to that of solid bars.

43, Fig. 4, is a shelf extending across the 70 rear end of the furnace, and resting on this shelf at the extreme right is a wearing-plate 43^a, over which the fresh bars are passed when being introduced into the furnace. In the continuous operation of the furnace the fresh 75 bars will be introduced into the openings covered by the plug 41^a; but it will be understood, however, that they may be introduced through any of the other openings.

44 represents vertical projections of the 80 bearing-bars 19, Figs. 1 and 3, resting against the side wall of the furnace, against which projections the bar or strip on the feeding-line will be in contact with the throat. These projections will prevent the closing up of the 85 gas-opening and are slightly beveled or rounded to facilitate the longitudinal movement of the bar.

The mechanism consisting of gears, sprocket-wheels, and sprocket-chains and operated by 90 the handles 45 and 46 (shown at Figs. 3 and 4) for moving the furnace to and from the reduction-rolls is of common and ordinary construction and forms no part of my present invention. The two handles 45 and 46 are simply intended for two men for controlling the 95 movement of the furnace.

While I show certain mechanism for controlling the operation of the pusher-bars or rams, I do not wish to be confined strictly 100 thereto, as it is quite evident that such mechanism can be changed to conform to the style of the furnace and the convenience of the operator. An essential feature, however, in connection with the pushers or rams for shoveling the bars across the floor are the openings in the side of the furnace for the admission of the said pushers or rams. While I show that said pushers or rams retreat to the inner 105 face of the side wall of the furnace, it will be understood that they can be withdrawn entirely from the furnace, if desired.

While I show one side or wall of the pockets or recesses 17 inclined, I do not wish to be strictly confined to this feature, as the principal object of these pockets is to catch and hold the falling dirt or dust, and thus prevent clogging the burners. For this purpose the burners discharge at right angles to the walls of said pockets, and the bottoms of said pockets 110 are below the mouth of the burners.

Having thus described my invention, what I claim as new, and desire to secure by Letters Patent, is—

1. A furnace of the character described provided with a combustion-chamber located beneath the work-supporting floor; bricks comprising the floor of said chamber constructed with pockets or recesses opening into said combustion-chamber; an opening in one of the side walls of the pockets, and pipes communicating therewith and with a gas-supply, for the purpose set forth. 125

2. A furnace of the character described pro-

vided with a combustion-chamber; bricks comprising the floor of said chamber provided with pockets or recesses opening into said combustion-chamber, and having one of their 5 side walls inclined and adapted to deflect flame projected therein and an opening into one of the side walls of the pockets and communicating with a gas-supply, as set forth.

3. A furnace of the character described provided with a combustion-chamber; bricks comprising the floor of said chamber, provided with pockets or recesses opening into said combustion-chamber, and constructed with side openings therein adapted to project 10 flame above the bottoms of said pockets or recesses, for the purpose set forth.

4. The combination, in a furnace of the

character described having a combustion-chamber, and floor-bricks therefor having pockets or recesses opening into said chamber, 20 of a gas-receiver and a series of gas-distributing conveyers placed below said floor-bricks, and pipes connecting said conveyers with the pockets of said floor-bricks, for projecting flame into said pockets or recesses, for the 25 purpose set forth.

Signed at Bridgeport, in the county of Fairfield and State of Connecticut, this 19th day of April, A. D. 1899.

THOMAS V. ALLIS.
